UNITED STATES PATENT OFFICE.

BAYARD G. WORTHINGTON, OF LOS ANGELES, CALIFORNIA.

CAN OPENER.

Application filed June 7, 1920. Serial No. 387,028.

To all whom it may concern:

Be it known that I, BAYARD G. WORTHINGTON, a citizen of the United States, and resident of Los Angeles, in the county of 5 Los Angeles, State of California, have invented certain new and useful Improvements in Can Openers, of which the following is a specification.

My invention relates to a can opener of 10 the character provided with renewable cutters and which may have various useful tools mounted in or formed in the handle, and the object thereof is to provide a device of that character which will be simple and efficient in operation and construction.

A further object is to provide a tool of 15 the character described which may have its cutter adjusted to operate from either direction, right or left, to accommodate the normal dexterity of the user.

A still further object is to provide a device of the above character in which the wearing parts are adjustable for wear.

Other objects and advantages will appear 25 hereinafter, and while I have shown and will describe the preferred form of my invention it will be understood that I do not limit myself to such preferred form but that various changes and adaptations may be 30 made therein without departing from the spirit of my invention.

In the drawings accompanying and forming a part hereof:

Figure 1 is a top plan of my device,

Fig. 2 is a side elevation of Fig. 1,

Fig. 3 is a top plan of the head of my device greatly enlarged,

Fig. 4 is a central longitudinal section of Fig. 3,

Fig. 5 is a detail view of the under side of the outer end of my cutter carrier, and

Fig. 6 is a top plan showing the operation of my device in cutting the top from a can.

Referring to the drawings, my device 45 comprises a handle 1 preferably formed of two narrow strips of thin metal 2 and 3 which are held spaced apart a suitable distance by a filler strip 4 of any suitable material, preferably wood. Strip 4 is shorter

50 in length than strips 2 and 3, and the projecting ends of said strips form a yoke 5. Provided in strip 3 at its projecting end is a rectangular aperture 6, and in strip 2 in register with aperture 6 is a hole 7. Mounted 55 between strips 2 and 3 at their projecting ends is a disk 8 provided on its outer periph-

ery with teeth 9 which teeth are adapted for engagement with the side of the can operated upon.

Disk 8 is provided with a central transverse opening 10 therethrough which is rectangular and in register with the opening 6 in strip 3 and normally rests upon said strip. Mounted upon disk 8 between the upper face thereof and the under side of strip 60 2 is my cutter carrier 11 in which is provided a hole 12 in register with hole 7 of strip 2. Disk 8 and carrier 11 are held positioned between strips 2 and 3 by means of pindle bolt 13, the lower end of which is 65 square to fit the hole 6 in strip 3 and hole 10 in disk 8, and its upper end is rounded to fit the holes 7 and 12 whereby disk 8 is non-revolubly held in respect to handle 1, and the carrier is rotatable in respect thereto. 70 Carrier 11 is provided with a plurality of holes 14 similar to hole 12 by means of which the center distance between the pindle bolt 13 and the cutter may be adjusted to suit various sizes of cans. My cutter comprises a 80 blade 15 and a screw-threaded portion 16 at opposite ends and having intermediate its ends a rectangular portion 17. The screw-threaded portion is adapted to be passed through an opening 18 in the outer end of 85 carrier 11 to project upwardly and the under side of carrier 11 is provided with rectangular recesses 19 and 20 adapted to receive portion 17 of the cutter whereby said cutter is held against rotation in respect to carrier 90 11.

The thumb-nut 21 provides means for detachably securing cutter 15 in its position of use, it being understood that the portion 17 will be positioned within the respective recess 95 19 or 20 according to whether it is to be used left-handed or right-handed, it being understood that the device as shown in the drawings is adjusted for right-hand use. Formed in strip 4 intermediate its ends is a 100 recess 23 opening outwardly in which is mounted a corkscrew 24 pivoted at one end so that the same may be swung outwardly for use, and in the opposite edge of strip 4 is a recess 25 in which is pivotally mounted 105 at one end an ice pick 26. Formed in the edges of strips 2 and 3 at the rear thereof are hooks 27 and 28 forming a bottle-opener or cap-remover.

In the use of my device as a can-opener 110 the device will be positioned as shown in Fig. 6, and by moving or swinging the han-

dle 1 alternately to the right and left the cutter will be caused to move around the top of the can each stroke to the left causing the cutter to cut out a portion of the top.

5 Having described my invention what I claim is:

A can opener comprising a handle formed of two narrow strips of thin metal, a filler spacing the two strips apart and forming 10 a yoke, a toothed disc mounted in the yoke, a cutter carrier mounted on top of the disc in the yoke, a pin inserted through the members of the yoke and through the cutter carrier and through the disc; a part of the pin 15 being squared to hold the disc from rotat-

ing in the yoke and a part being rounded to allow the cutter carrier to rotate, there being a plurality of holes in the cutter carrier for adjustment in relation to the pin and there being a cutter hole with right and 20 left recesses, a cutter comprising a blade and a rectangular portion to fit in either recess and a screw threaded portion to extend through the hole, and a thumb nut upon the screw threaded portion.

In witness that I claim the foregoing I have hereunto subscribed my name this 14th day of May, 1920.

25
BAYARD G. WORTHINGTON.
